UNITED STATES PATENT OFFICE.

JAMES W. KEELEY, OF PHILADELPHIA, PENNSYLVANIA.

POWER-HAMMER.

No. 904,701.

Specification of Letters Patent.

Patented Nov. 24, 1908.

Application filed March 4, 1908. Serial No. 419,205.

To all whom it may concern:

Be it known that I, JAMES W. KEELEY, citizen of the United States, residing at Philadelphia, in the county of Philadelphia and State of Pennsylvania, have invented 5 certain new and useful Improvements in Power-Hammers, of which the following is a specification.

This invention comprehends certain new 10 and useful improvements in power hammers of the fluid operated type, and the invention has for its object simple, durable and efficient means for guiding the die of the hammer in its operation so as to effect the completion 15 of the operation quickly and in an effective manner.

While the invention is applicable to riveting hammers generally, it is designed in the present instance particularly for riveting 20 stay bolts or stay rods, of boilers, while the rivet ends of such bolts or rods are either hot or cold.

With this and other objects in view as will more fully appear as the description proceeds, the invention consists in certain constructions, arrangements and combinations 25 of the parts that I shall hereinafter fully describe and then point out the novel features in the appended claim.

For a full understanding of the invention and the merits thereof, reference is to be had 30 to the following description and accompanying drawings, in which:

Figure 1 is a side elevation of a fluid 35 operated power hammer provided with the improvements of my invention; Fig. 2 is an enlarged longitudinal sectional view of the die end of the hammer with my invention applied; Fig. 3 is a similar view illustrating 40 the application of the device at different stages of its operation; and, Fig. 4 is a diagrammatic view, hereinafter specifically referred to.

Corresponding and like parts are referred 45 to in the following description and indicated in all the views of the drawings by the same reference characters.

Referring to the drawing, the numeral 1 designates the body portion of a pneumatic 50 or other fluid operated power hammer, which may be of any desired design or type suitable for riveting, and 2 designates the die thereof, said die being provided with a convex striking head 3.

55 My invention consists essentially of a guide member for holding the hammer prop-

erly against the work and controlled by the ordinary skill of the riveter. In the present instance, the said guide member, designated 4, embodies a sleeve which is substantially 60 cylindrical as shown, although it is to be understood that my invention is not limited in this respect, but that any modification of such sleeve may be made that will come within the scope of the invention as defined 65 in the appended claims. The guide member 4 is shaped on its interior at one end, as indicated at 5, so that it may be readily slipped over the end of the body portion 1 of the hammer and it may be properly secured to said body portion by any desired means. In the present instance, I have shown, for this purpose, a split ring 6 which is preferably constructed of comparatively 70 heavy spring steel of the best quality and 75 which is formed with inwardly turned lower and upper ends that are designed to fit snugly in annular grooves 7 and 8 formed in the contiguous ends of the guide member 4 and body portion 1, respectively. The 80 clasping ends of the ring 6 should be preferably so made that when the ring is applied to the hammer and to the guide member, the split portion or ends will meet, and care is to be taken in the construction and proportion 85 of the parts that they will so fit together when joined as to avoid or minimize movement of the guide member that the vibration of the hammer would tend to produce.

In the practical operation of my invention, which may be either embodied as a permanent part of the hammer or as an attachment therefor and capable of being removed therefrom, the guide member 4 is rested, say, against the outer face of a boiler 90 sheet A, the stay bolt or stay rod a to be riveted projecting into the open outer end of the guide member, the interior wall thereof at such end resting against the side of the bolt end to be formed. The pneumatic, 100 steam, or other fluid pressure is then turned on to effect the accustomed repeated vibration of the hammer against the riveting die 2 and in the operation of forming the head, the tool is given a circular rolling movement 105 upon the stay bolt or stay rod, as a pivot, such motion being an eccentric motion as will be evident and being preferably free from any sliding connection between the interior wall of the guide member 4 and the 110 bolt. By such motion, it will be clear that the die will be carried around the margin of

the bolt or rod for the initial and subsequent spreading or mashing operations until the bolt is finally and effectively shaped.

In Fig. 3 is illustrated in full lines a bolt 5 partially completed and in dotted lines, in finished condition. In Fig. 4, is illustrated in full and dotted lines and diagrammatically, two positions of the die and guide member upon the head of the stay bolt or 10 rod, it being clear from this view, that the guide member has imparted to it an eccentric rolling or rotary motion upon the rod *a* as a pivot, in the direction of the darts, commencing, say, at the point *x* around to the 15 point *y* and so on, until the bolt has been finally formed.

It is to be particularly noted, that by the means of my invention, the ball shaped or convex head 3 of the rivet die 2 bears at all 20 times upon the end of the stay bolt or rod to be formed into a rivet, at a point diametrically opposite to the point of contact between the interior wall of the guide member 4 and the side of such end. This permits the 25 riveting die to hammer or rivet but a small portion of the stay rod or bolt at one time, and insures that the stay-bolt will be steam tight after completion and properly rounded, as indicated in dotted lines in Fig. 3.

30 From the foregoing description in connec-

tion with the accompanying drawing, it will be seen that I have provided a very simple, durable and efficient construction of means for guiding a riveting die in operation, which will result in the formation of a properly 35 rounded and steam tight bolt in a very expeditious manner, thereby saving time and effecting economies in the manufacture of boilers and other articles to which my invention is applicable. 40

Preferably the guide member 4 is formed near its outer end with a plurality of openings 9, so that the workman may at all times view the work as it progresses.

Having thus described the invention, what 45 is claimed as new is:

The combination with a hammer of the character described, and its die, of a guide member carried by the hammer and provided with an opening of greater diameter 50 than the operative surface of the die, the die being formed with a convex striking head, as and for the purpose set forth.

In testimony whereof I affix my signature in presence of two witnesses.

JAMES W. KEELEY. [L. S.]
